UNITED STATES PATENT OFFICE

BENJAMIN F. LEE, OF NIAGARA FALLS, NEW YORK

DESIGN FOR A LAMP OR SIMILAR ARTICLE

Application filed April 8, 1933. Serial No. 47,735. Term of patent 14 years.

To all whom it may concern:

Be it known that I, BENJAMIN F. LEE, a citizen of the United States, residing at Niagara Falls, Niagara County, State of New York, have invented a new, original, and ornamental Design for a Lamp or Similar Article, of which the following is a specification, reference being had to the accompanying drawing forming a part thereof.

In said drawing:

Fig. 1 is a perspective view of a lamp embodying my design.

Fig. 2 is a fragmentary side elevation, having the lower part of the stand broken away and the dotted outline of the shade and the electric light bulbs omitted therefrom.

I claim:

The ornamental design for a lamp or similar article, substantially as shown.

BENJAMIN F. LEE.
